UNITED STATES PATENT OFFICE.

JOSEPH E. CHAPPATTE, OF NARBERTH, PENNSYLVANIA.

TASSEL AND PENDANT.

Application filed September 28, 1920. Serial No. 413,398.

To all whom it may concern:

Be it known that I, JOSEPH E. CHAPPATTE, a citizen of the United States, residing at Narberth, in the county of Montgomery and 5 State of Pennsylvania, have invented certain new and useful Improvements in Tassels and Pendants, of which the following is a specification.

Prior to my present invention, decorative 10 tassels and pendants, such for example as are used on curtains, draperies and window shades, etc., have been made with various ornamental coverings. These coverings are usually made by first winding threads of 15 silk yarn upon wooden forms so as to completely cover the wood after which silk cord is netted over the wound yarn before the fringe is attached. This previous method of making tassels and pendants re- 20 quires great skill since most of the work is done by hand and said netting must be done by hand and shaped to the various contours of the forms. Sometimes a number of forms are individually covered and secured 25 together by various means so as to produce different designs of tassel heads or pendants and furthermore the construction is expensive and it is difficult to secure persons who are capable and willing to undertake such 30 tedious tasks.

One object of my present invention is to quickly and cheaply produce tassels and pendants for the above mentioned purpose which will present substantially the same 35 effect to the eye as tassels and pendants made in accordance with that above described; my present invention consisting primarily in molding or otherwise producing the tassels and pendants in a manner so 40 that the outer surface will include an integral structure representative of wound and netted cords or threads which will have an appearance similar to the separately covered tassel heads and pendants above 45 mentioned.

Another object is to make my improved tassel heads and pendants in such manner that bullion or other styles of fringe can be secured thereto in such manner that the resulting structure will be durable and extremely pleasing in appearance.

These objects, and other advantageous ends which will be described hereinafter, I attain in the following manner, reference

being had to the accompanying drawings in 55 which—

Figure 1 is an elevation showing a tassel made in accordance with my invention,

Figure 2 is a sectional elevation illustrating how the tassel head shown in Figure 1 60 is molded; the section being taken between the halves of a mold,

Figure 3 is a transverse section taken on the line 3—3 of Figure 2,

Figure 4 is a sectional elevation through the completed tassel; a part of the fringe being cut off at the bottom,

Figure 5 is an elevation showing another form of tassel made in accordance with my present invention,

Figure 6 is a transverse section taken on the line 6—6 of Figure 5, and

Figure 7 is a longitudinal section of the tassel head illustrated in Figures 5 and 6.

In making a tassel or pendant in accordance with my present invention, I may use any material which may be molded or pressed into form so that after the molding or pressing operation, the material will harden or set. For example I may use celluloid, plastic compositions or any other material which can be molded by pouring or pressing the same into shape and if desired the material may be tinted by painting, dyeing or otherwise coloring the same to produce various effects; said coloring either being present in the molding or pressing operation or it may be applied after the tassel head or pendant is formed and hardened.

Referring to the drawings and particularly to Figures 1 to 4 inclusive, I make my improved tassel head 8, one form of which is shown in Figure 1, by providing a mold 9 which is made in two sections 10 and 11 as shown in Figures 2 and 3. This mold is made to provide a cavity 12 which leads downwardly from its top 13 and terminates in a closed bottom as shown at 14. The surface of the cavity 12 is cut out to provide grooves 15 of such shape that when material, out of which the head is to be made, is poured into the cavity that said material will fill said grooves and after the material has set or hardened and the sections 9 and 10 of the mold have been opened to permit the release of the head that the portion of the material which entered the grooves 15 will be in the form of projections 16 represent-

ing a netted covering for the body portion 17 of the tassel top. In other words the grooves 15 are cut or otherwise formed in such manner within the mold sections that 5 they will shape the material in the form of intertwined or netted threads which while they are integral with the body portion 7, will give the appearance of threads or cords which have been netted around the body 10 portion 17. Furthermore the inner surface of the cavity 12, as shown in Figures 2 and 3, has been shaped to provide a portion 18 having the representation of a band or ring surrounding the body portion 17 between its 15 ends; there being present a portion 19 having the appearance of individual windings of thread or yarn.

It is thus obvious that by cutting or otherwise forming the inner surface of the cavity 20 12 that the molded material therein can be given various effects representing threads or yarn which covers the body portion and by tinting either integrally or superficially the molded structure may be given a very 25 pleasing appearance so as to represent a covering of yarn and netted cords such for example as illustrated in Figure 1. In order to provide means of attachment of fringe 20 to the head 8, I insert a convex 30 filling piece 21 in the bottom of the cavity 12 and insert a core rod 22 upwardly through the filling piece and cavity 12 so that the resulting molded structure, as clearly shown in Figure 4, will have a recess 23 in its bottom and a central hole 24 leading upwardly 35 from the recess to the top of the head whereby an attachment cord 25 can be inserted; said attachment cord extending through a button 26 and being knotted at 24^a below 40 the bottom and at 28 above the top of the head 8. The fringe 20 may be formed of any of the type having a heading which can be wound around the attachment cord directly above the button 26, after which the 45 attachment cord can be pulled upwardly to firmly clamp the heading of the fringe within the recess and the knot 28 can then be formed so as to hold all of the parts in place. If desired the upper surface 27 of 50 the recess 23 can be coated with adhesive material so as to guard against any possible slipping of the fringe out of the recess and in this manner a strong and durable tassel

can be produced; the heading of the fringe not being visible since only the strands of 55 the fringe will depend below the head 8 as clearly shown in Figure 1.

In Figures 5, 6 and 7 I have illustrated another type of design in which the molded head 8^a has the appearance of wavy cords 60 which are wound around a body portion and since the other parts are similar to that described in connection with Figures 1 to 4, I have given similar parts corresponding reference numerals. 65

While I have described my invention as taking a particular form, it will be understood that the various parts of my invention may be changed without departing from the spirit thereof, and hence I do not limit 70 myself to the precise construction set forth, but consider that I am at liberty to make such changes and alterations as fairly come within the scope of the appended claims.

Having thus described my invention, what 75 I claim as new and desire to secure by Letters Patent is:—

1. An ornamental tassel block of plastic material having upon its outer surface an integral design in relief. 80
2. An ornamental tassel block of plastic material having upon its outer surface an integral design in relief representative of fabric.
3. An ornamental tassel block of plastic 85 material having upon its outer surface an integral design representative of a ring.
4. An ornamental tassel block of plastic material having upon its outer surface an integral design in relief representative of 90 fabric and a design representative of a ring.
5. An ornamental tassel block of plastic material having upon its outer surface an integral design in relief representative of 95 fabric and provided with a central bore adapted to receive a suspending cord and with a concavity at its bottom adapted to receive a fringe.

In testimony whereof I have signed my name to this specification in the presence of 100 two subscribing witnesses.

JOSEPH E. CHAPPATTE.
